MILK CAN PLANTER

William A. Bamesberger, P.O. Box 1442,
Auburn, Calif. 95603

Filed Apr. 17, 1973, Ser. No. 351,857

Term of patent 14 years

Int. Cl. D11—02; D9—02

U.S. Cl. D35—3 B

FIG. 1.

FIG. 2.

FIG. 3.

FIG. 4.

FIG. 1 is a perspective view of a milk can planter;
FIG. 2 is a top plan view of the invention;
FIG. 3 is a side elevation of the invention; and
FIG. 4 is a bottom plan view of the milk can planter.

The characteristic features of my design reside in the specific configuration of the circumferential trough member, as best illustrated in FIGS. 1 and 3 on the drawing.

I claim:

The ornamental design for a milk can planter, substantially as shown.
